UNITED STATES PATENT OFFICE.

THOMAS KEENAN, OF BROOKLYN, NEW YORK.

CLEANING FEED-WATER REGULATORS.

No. 907,606.

Specification of Letters Patent.

Patented Dec. 22, 1908.

Application filed January 22, 1908. Serial No. 412,204.

To all whom it may concern:

Be it known that I, THOMAS KEENAN, a citizen of the United States, residing at Brooklyn, in the county of Kings and State 5 of New York, have invented new and useful Improvements in Cleaning Feed-Water Regulators, of which the following is a specification.

This invention relates to means by which 10 an inlet valve of a feed water regulator for a boiler or other appliance can be readily washed or flushed clean. In case of a boiler or the like the pressure therein can also be made to serve as a means for cleaning or 15 blowing out any sediment that is lodged on the seat of the inlet valve.

This invention is set forth in the following specification and claim and illustrated in the annexed drawing in which—

20 Figure 1 shows a cleaning feed regulator embodying this invention. Fig. 2 shows a modification.

The feed water regulator comprises an inlet pipe *a* outlet pipes *b* *b* and a float *c* connected to an inlet valve *e*; these parts are not new. The new feature of the invention consists in providing the feed water regulator with a passage or channel *f* located below the inlet valve *e* and having an outlet cock or 30 valve *g* at the end of the passage *f*. The passage or outlet *f* is formed by a division wall *k* overhanging the outlet *f*, and inlet water from *a* will carry any sediment contained therein to the inner end of said passage under 35 the valve *e*. Such sediment is prevented from being caught or trapped at such end of the passage under valve *e* as on opening valve *g* the current from inlet opening *a* will sweep about the end of the partition or division wall *k* and wash away any accumulation or mud at the end of the passage under the valve *e*. The feed water inlet *a* communicates with said passage *f* and when the outlet valve *g* is opened the mud and other 45 sediment which has accumulated under the automatic valve *e* will be flushed out through the said outlet valve.

In case any obstruction has lodged on the seat of inlet valve *e* the same can be removed 50 as follows. The inlet *a* is closed and the blow off cock *g* is opened. Then the valve *e* being held by said obstruction from its seat steam from the float chamber will blow through the valve passage and clean out the 55 same or dislodge the obstruction. In case a heavier float is used a counterweight as

shown at *h* Fig. 2 can be applied. If valve *e* should be blocked or stopped for any reason then by opening direct feed *i* water will flow from the main *a* through direct feed valve *i* 60 to the boiler or float chamber.

The direct feed *i* is formed or bored through a casting or block in which same casting is formed or bored the outlet or passage *f* and the seat for the valve *e*. By applying such one piece casting, all the required feeds or passages with valve seat are likewise applied. Such casting is readily applied by bolts or suitable fastening means. The valve *e* is applied against the valve seat 70 from the interior so that pressure in the boiler will tend to press the valve to close the seat or check waste or outflow through passage *a*. By having the valve not secured to but loose from the float *c* or the lever actuated by the float, the latter can sink or move away from the valve and the latter will be still held by the pressure in the boiler to the valve seat in case the inflow pressure from feed *a* is interrupted or weak while the level 75 of water in the boiler is low. As the level of water in the boiler rises and moves the float, the valve, if open, is pressed back to its seat by the lever from the float.

I claim—

85 A cleaning feed water regulator for low pressure steam boilers or hot water heating plants and the like, comprising a block adapted to be secured to such boiler and provided with an inlet valve seat, an inlet valve 90 and a direct feed passage leading into the valve seat and continuing on, under and by said seat, a division wall about which said passage leads, said passage terminating in a downwardly extending portion provided 95 with outlet valve and forming a sediment or mud chamber under the division wall and inlet valve seat so as to enable sediment under the inlet valve seat to be carried past the same and to separate from the feed water 100 before the latter is allowed to pass into the inlet valve seat, said passages being all formed in said block to be attached and detached with the same.

105 In testimony whereof I have hereunto set my hand in the presence of two subscribing witnesses.

THOMAS KEENAN.
